MICROPHONE

Robert Louis Deschamps, Chicago, Ill., and Richard E. Petrie, Benton Harbor, Mich., assignors to Shure Brothers, Incorporated

Filed July 27, 1961, Ser. No. 66,092

Term of patent 14 years

(Cl. D26—14)

We claim:

The ornamental design for a microphone, substantially as shown.
